LIQUEFIED GAS SYSTEM

Rosswell W. Thomas, Birmingham, Mich., assignor to Phillips Petroleum Company, a corporation of Delaware

Application October 1, 1938, Serial No. 232,858

3 Claims. (Cl. 62—1)

The present invention relates to systems for dispensing liquefied gas.

In the usual liquefied gas system such as fuel gases like propane, butane, and similar liquefiable gases, the customer has on his premises a supply tank which is filled periodically from a tank truck belonging to the dealer. In the system there is a connection between the vapor space above the liquefied gas in the supply tank and the appliances which utilize the gas, the pressure being reduced from that in the tank to that desirable for the appliances by a gas pressure regulator. Numerous safety devices are usually associated with the supply tank to reduce the hazard of handling high pressure, highly combustible gases. In the past the supply tank, which was located above or below the ground, had a plurality of openings to receive the filling valve, vapor withdrawal valve, and the safety devices. Sometimes some of these elements were combined so as to have less openings in the tank and to simplify the connections in general. Such equipment is shown in U. S. Patent 1,977,268 issued to Paul S. Endacott and U. S. Patent 2,047,339 issued to Rosswell W. Thomas. Co-pending application, Serial No. 151,016 filed January 29, 1937 by George R. Benz shows similar equipment of this nature. However all the equipment previously developed has many disadvantages, among which is the lack of mechanical simplicity in arrangement of the necessary valves and safety devices.

The combination of all the equipment into one unitary fixture has not heretofore been achieved because, for example, continuous flow of the vapor through the service line to the appliance is a prerequisite and must continue while the tank is being replenished. Also, an excess pressure valve and a fusible member must always be in communication with the interior of the supply tank. An excess flow valve must be positioned somewhere in the vapor withdrawal line but must not prevent a high rate of flow of vapor through the relief valve.

An important object of the present invention, therefore, is to provide a liquefied gas system in which the filling, vapor withdrawal, and safety devices are incorporated in a simplified structure.

In the accompanying drawings, forming a part of this specification, and in which like numerals are employed to designate like parts throughout the same,

Figure 1 is a view in elevation, with portion

broken away, of a system incorporating the invention.

Fig. 2 is a plan view of the system of Figure 1,

Fig. 3 is an enlarged view in elevation, with the safety valve in cross section, of the unitary fixture shown in Figures 1 and 2,

Fig. 4 is a longitudinal section taken on the line 4—4 of Figure 3,

Fig. 5 is a view in cross section taken on the line 5—5 of Figure 3, showing only the stand pipe,

Fig. 6 is a plan view of another embodiment of the fixture shown in Figures 3 to 5 inclusive,

Fig. 7 is a view in longitudinal section on the line 7—7 of Figure 6 with some parts in elevation, and

Fig. 8 is a view in longitudinal section taken on the line 8—8 of Figure 6 with some parts in elevation.

Referring first to Figures 1 and 2, reference numeral 10 indicates a cylinder for holding the liquefied gas. Welded or otherwise fastened into cylinder 10 is a sleeve or boiler flange 11, screw threaded to receive a stand pipe 12 which in turn terminates in an integral fitting 13 to be later more specifically described. Fitting 13 has connection through a conduit 14 with a standard gas pressure regulator 15. Regulator 15 has the usual pressure relief valve 16 interposed before service line 17. A leg 18 helps support the regulator safety relief valve and service line. Service line 17 turns downwardly after leaving the safety relief valve so that a protecting cap (not shown) can be used, of the type disclosed in co-pending application Serial No. 147,116 filed June 8, 1937 by the present inventors.

In operation of the system shown in Figures 1 and 2, the cylinder 10, which may be located above or below ground level, is filled with liquefied petroleum gas by means of a pump and connecting pipe (not shown) which are connected to a part of fitting 13. At the same time regulator 15 through conduit 14 and fitting 13 is in communication with the gas space above the liquefied gas and will deliver gas to service line 17 as required.

Referring more specifically to Figures 3, 4, and 5, wherein the fitting designated generally by reference numeral 13 is shown in detail, a valve body is shown at 19 which is integrally connected to the upper end of stand pipe 12. As explained above, stand pipe 12 makes threaded connection with sleeve 11 and gland 21, carrying packer 22, seals the connection. Valve body 19 contains two major valves indicated generally at 23 and 24.

Valves 23 and 24 close a pair of conduits or passages 25 and 26 respectively, extending through the valve body 19 and stand pipe 12. A third conduit 27 extends upwardly through stand pipe 12 and into valve body 19 to terminate in a screw threaded port 28 which receives a safety valve 29 which will later be described in detail. Concentrically positioned within conduit 26 is a tube 30 extending up through the stand pipe to a fastening point within valve body 19 and downwardly past the lowermost extremity of stand pipe 12 to a point which, when fitting 15 is connected to cylinder 10, would be a desirable liquid level for the cylinder when filled. At the point where tube 30 is fastened to valve body 19, a 15 bleeder passage 31 is formed in the valve body and places the upper end of tube 30 in connection with a port formed by valve seat 32. Valve seat 32 is at the bottom of a threaded recess 33 which receives a threaded plug 34, the innermost 20 end of plug 34 acting as a valve face for engagement with valve seat 32. A second bleeder passage 35 connects the lower part of recess 33 with atmosphere.

The lower end of conduit 25 has associated therewith an excess flow valve indicated generally at 36 and comprising a valve disk 37 slidably carried on a pair of guides 38. As stated previously, the upper end of conduit 25 is controlled by valve 23 which when open, allows conduit 25 to communicate with a conduit 39 which in turn communicates with a screw threaded coupling member 40 adapted to be connected to conduit 14 shown in Figures 1 and 2. Similarly valve 24, when open, places conduit 26 in communication with a conduit 41 which in turn opens into a threaded coupling 42 adapted to be connected to the hose (not shown) of a filling truck. Since valves 23 and 24 are similar, varying only in size because filling valve 24 handles liquid and service line valve 23 handles vapor, a description of one will suffice for both, the same reference numerals being applied to like parts. Considering valve 23, a valve seat 43 surrounds the upper terminal of conduit 25 and a valve plug 44 carrying a resilient valve face 45 is movable into or out of sealing engagement with valve seat 43. Movement of valve plug 44 toward and away from valve seat 43 is effected through swivel member 46 engaging with a plug 47 which in turn has screw thread connection with a retainer member 48. Retainer member 48 remaining stationary, rotation of plug 47 acting on swivel member 46 moves valve plug 44. Instead of the usual packing gland, a diaphragm sealing means is used, thus a diaphragm 49 held between valve plug 44 and swivel member 46 by a pair of nuts has its peripheral edges clamped between a flange 50 formed in valve body 19 and the lower extremity of retaining member 48. A screw threaded connection between retaining member 48 and valve body 19 permits a sealing and clamping action on diaphragm 49.

Referring specifically to safety valve 29 shown in Figure 3, the same comprises a valve housing 51 having an integral valve seat 52 surrounding a passage 53 which is in communication with coupling 28 the latter being in screw fitting relation with housing 51. The end of housing 51 is closed by perforated spring retainer 54. Slidable in housing 51 is a valve plug 55 having a resilient valve face 56 adapted to cooperate with valve seat 52. Guide members 57 hold valve plug 55 for sliding movement in the housing 51 while allowing vapor to pass. Spring 58 is po-

sitioned between spring retainer 54 and valve plug 55 and urges the valve plug into closing position in opposition to the gas pressure in the cylinder.

Connected to conduit 26 below valve 24 is a large threaded port 59 which receives a threaded plug 60 carrying a heat fusible member.

Valve body 19 has integrally formed therewith a lifting eye 53' by means of which cylinder 10 can be lifted, if desired.

In use, with the fitting 13 sealingly connected to cylinder 10 through stand pipe 12 and sleeve 11, as stated above, conduit 14, regulator 15, and the remaining service fittings, will be connected to coupling 40 with valve 23 in open position. When it is desirable to replenish the liquefied petroleum gas in cylinder 10, a supply tank, and hose (not shown) are connected to coupling 42. Since vapor passage 25 is separate from passage 26, discontinuance of the service is not necessary. Liquefied petroleum gas from the supply tank is either pumped or run by gravity into cylinder 10 through passage 26 in the space surrounding tube 30. When the operator judges that the proper liquid level line is being approached, plug 34 is turned so that vapor is allowed to escape from tube 30 through bleeder passage 31 and bleeder port 35. When the liquid level reaches the lower extremity of tube 30, the liquefied petroleum gas will be expelled through bleeder port 35 forming a white foggy discharge which will notify the operator that cylinder 10 is filled to the proper height.

In case the service equipment anywhere from valve 23 to the utilization equipment should become damaged so that gas begins to rush past valve 23 at an excessive rate, excess flow valve 36 will be moved upward by the increased pressure drop across it closing the lower end of conduit 25. This action cuts off the excessive flow of gas but since valve disk 37 does not make an absolutely perfect seal with the lower end of stand pipe 20, enough gas leaks by so that when the damage to the service equipment has been repaired the pressure builds up in the service line and valve 36 opens by the action of gravity. If for any reason the pressure in cylinder 10 becomes excessive, relief valve 29 opens, permitting vapor to be vented to the atmosphere through conduit 27. Where a fire adjacent the installation raises the temperature of the equipment to a dangerous point, fuse plug 60 gives way, placing conduit 26 in communication with the atmosphere.

Referring specifically to Figures 6, 7, and 8, a modification of fitting 13 is shown which has many advantages therover and is adapted to be used in place of fitting 13 in the system shown in Figures 1 and 2. In this embodiment reference numeral 61 indicates the valve body integrally connected to the top of stand pipe 62 which has threaded thereon a packing gland 63 and a gasket 64. Stand pipe 62 is bored to form one large passage 65 which extends up into valve body 61. In the neighborhood of the upper end of the large passage, valve body 61 has a projecting arm 66 and is bored at right angles to passage 65 for some distance into arm 66 forming at that point valve chamber 67 having a valve seat 68 which surrounds a port 69 which in turn is enlarged into a coupling 70. At the point where port 69 is enlarged into the coupling 70, a flared surface 71 is formed. Passage 65 as it extends upwardly into valve body 61 has a reduced portion 72 having a threaded section

72' which receives an externally threaded tube 74 to position the same concentrically with respect to passage 65.

Tube 74 has a flared portion 74' at its lowest extremity. In the neighborhood of the reduced portion 72, valve body 61 has an arm 73 extending at right angles to passage 65 and at right angles to arm 66, as shown best in Figures 6 and 8. This arm has a longitudinal passage 73' bored therethrough and extending across reduced portion 72 to form a valve chamber 75. Diagonally opposite arm 73 and in alignment therewith, valve body 61 presents another arm 76 which has a threaded coupling 77 with an annular gasket 78 positioned at its inner end. Arm 76 is further drilled at 79 with properly diminished threaded sections to place valve chamber 75 and coupling 77 in communication. The threaded sections, just referred to, cooperate with and hold a conventional tire valve core 80.

In valve chamber 67 a valve 81 having a resilient valve face 82 is slidably positioned with a spring 83 acting between tube 74 and valve 81 to bias the same into closing position with valve seat 68.

The reduced portion 72 of passage 65 has connected thereto a small threaded port 84 which in turn connects to a bleeder passage 85 which terminates in a valve seat 86 at the inner extremity of a threaded bore hole 87. A tube 88 externally threaded at its upper end is held in threaded port 84, the tube extending downwardly when the fitting is connected to cylinder 10 to the desired liquid level as in the case of tube 30 shown in Figures 3 and 4. In bore hole 87 is positioned a plug 89 having a valve face 90 adapted to engage valve seat 86. A bleeder port similar to bleeder port 35 shown in Figure 3 connects the lower portion of bore hole 87 with the atmosphere.

The passage terminating at one end in valve chamber 67 is closed at the surface of the valve body by a plug 91 having a fusible element 92. Coupling 10 is shown closed by removable sealing plug 93. Arm 73 has screw threaded thereon a safety relief valve 94, the same as that shown at 29 in Figure 3, which closes passage 73' in opposition to the pressure therein. At the other end of passage 73' in chamber 75 an excess flow valve 95 is slidably positioned with a spring 96 urging valve 95 into contact with liquid level indicator tube 88. It will be understood that the body of valve 95 is spaced from the walls of valve chamber 75 by guides, not shown for the purpose of clarity, which allow the vapor to pass the valve.

At its upper end valve body 61 terminates in a well 97 which receives a bayonet 98 retained therein by a cotter pin 99.

In use the embodiment shown in Figures 6, 7, and 8, is similar to fitting 13. With this embodiment stand pipe 62 is threaded into sleeve 11 and the connection sealed by a packing gland 63. In using the present embodiment, however, conduit 14 carries a coupling which upon making a seal with gasket 78 of arm 76 opens tire valve core 79 placing the interior of cylinder 10 in communication with the surface fitting. Since tire valve 79 is urged into closing position by the gas in cylinder 10 and the spring of the tire valve core, no additional valve is needed to close passage 79. Excess flow valve 95 in the present embodiment operates under the same conditions as excess flow valve 36, the only difference being that valve 95 is not in a vertical position,

a spring is added to retain it in open position. When it is desired to replenish liquefied petroleum gas in cylinder 10, plug 93 is removed and a filling hose is used which makes sealing connection with surface 71, the superior pressure of the liquefied gas in the hose forcing valve 81 open. Since the liquefied petroleum gas being run into cylinder 10 passes through passage 65 in the space outside of tube 74, the system can remain in service. Flared portion 74' of tube 74 throws liquefied gas outwardly and prevents the same from being carried up into the inside of tube 74 and out into the service system. As in the previously described embodiment the liquid tube is used to determine when the liquefied gas in cylinder 10 has reached the proper level. Fuse plug 91 and safety relief plug 94 have identical functions as do the corresponding elements in the previously described embodiment. Bayonet 98 is a means for fastening a cover in place.

20 It is to be understood that the form of this invention, herewith shown and described, is to be taken as a preferred example of the same, and that various changes in the shape, size, and arrangements of parts, may be resorted to, without departing from the spirit of the invention, or the scope of the subjoined claims.

I claim:

1. A unitary fitting for use with a liquefied gas container, comprising a body, a conduit therein placing said container in communication with a filler connection on said body, valve means associated with said conduit, a second conduit within said first-named conduit for placing the interior of said container in communication with a vapor withdrawal connection on said body, valve means associated therewith for controlling the flow of fluid therethrough, said body having a passage connecting the filling conduit with the exterior of the fitting, said passage being normally closed by fuse metal, said body also having an opening placing one of said first-named conduits in communication with the atmosphere, a safety relief valve associated with said opening and normally closing the same, a third conduit in said valve body placing the interior of said container in communication with the atmosphere and a liquid level indicator valve associated with said last-named conduit and normally closing the same.

2. A liquefied gas dispensing system comprising a container for the liquefied gas, a fitting on the container, said fitting having a liquid filling passage therein communicating with said container and a vapor withdrawal passage therein communicating with said container, said fitting having a further passage connecting the liquid filling passage with the exterior of the fitting, said last passage being normally closed by fuse metal.

3. A liquefied gas dispensing system comprising a container for the liquefied gas, a fitting on the container, said fitting having a liquid filling passage therein communicating with said container and a vapor withdrawal passage therein communicating with said container, said fitting having a further passage connecting the liquid filling passage with the exterior of the fitting, said last passage being normally closed by fuse metal, a conduit within said filling passage placing the interior of said container in communication with the atmosphere, and a liquid level indicating valve associated with said last named conduit.

ROSSWELL W. THOMAS.
